PORTABLE TOOL HOUSING FOR CUTTING IMPLEMENT

Charles A. Mattson and William V. Kalnins, Oak Park,
Ill., assignors to Sunbeam Corporation, Chicago, Ill.,
a corporation of Illinois

Filed May 29, 1962, Ser. No. 70,345

Term of patent 14 years

(Cl. D40—1)

FIG. 3.

FIG. 4.

FIG. 5.

FIG. 1 is a perspective view of a portable tool housing for cutting implements showing our new design, the shearing comb and cutter head are shown in broken lines for illustrative purposes only;

FIG. 2 is an enlarged bottom plan view thereof;

FIG. 3 is a side elevational view of FIG. 2;

FIG. 4 is a front elevational view thereof; and

FIG. 5 is a rear elevational view thereof.

The essential features of our design reside in those portions shown in full lines.

We claim:

The ornamental design for a portable tool housing for cutting implements, as shown and described.
